UNITED STATES PATENT OFFICE

OSCAR ANTON WIBERG, OF FINSPONG, SWEDEN

REGULATING MECHANISM FOR STEAM OR GAS TURBINES

Application filed September 18, 1925, Serial No. 57,255, and in Sweden September 18, 1924.

The present invention relates to regulating mechanism for elastic fluid turbines, as steam or gas turbines, and more particularly to regulating mechanisms for turbines having two oppositely running rotors.

The object of this invention is to provide a regulating mechanism in which the throttling of the working steam may be reduced, practically to any degree desired.

10 In the accompanying drawing the invention is illustrated as applied to a radial flow turbine.

Figure 1 is an axial section of part of a back-pressure turbine of the radial flow type having two oppositely running rotors provided with a regulating mechanism according to this invention.

Fig. 2 is a cross section on the line A—A of Fig. 1 and elevation of the governor mechanism associated therewith.

With reference to the drawing it is to be noted that Fig. 1 shows a quarter of the turbine only. For the sake of the description it should be kept in mind that the turbine is symmetrical with respect to the vertical and horizontal dotted lines shown in this figure.

With reference to Fig. 1, the numerals 9, 8, 7 denote successive sections of the rotary blade system of a radial flow turbine, having oppositely rotating rotors, and 15 is one of the turbine shafts. 11 indicates the stationary turbine casing, and 12, 13 are the members of a labyrinth packing disposed between the blade system and the stationary casing. Said members are also for the purpose of balancing the axial thrust due to the pressure of the driving medium upon the rotary system.

Situated at the outer side of the packing member 13 at each side of the turbine is an annular regulating slide valve 2 which is contained in the supply chamber for the driving medium 1. Said slide valve is rotatable relatively to the axis of the turbine. Formed in the slide valve 2 are a number of concentric sets of apertures 3, 4 by means of which the supply of driving fluid to passages 5, 6 leading through the packing members 12, 13 to various points of the blade system may be controlled.

50 In Fig. 2, I have shown the annular valve 2

connected to the governor of the turbine to secure an automatic operation of the valve in response to the load. The rotary valve 2 is connected by the link 20 to one end of a lever 21 pivoted at 22 and the opposite end of which is connected by the link 23 to the stern 24 of the centrifugal governor 25.

55 The operation is as follows—

Between the chamber 1 and the inlet point 10 of the blade system there is an always 60 open connection through which the driving medium passes when the turbine is in operation. At low load the entire amount of driving medium enters at 10 because the entrance to passages 5 and 6 is cut off. At somewhat 65 higher loads the entrance to the passages 5 opens so that driving medium will flow from chamber 1 through 3—5 directly to blade system section 8.

70 The driving medium (as over load steam) expands through the blade system sections 8 and 7, whereas the driving medium entering at 10 expands through all sections 9, 8, and 7. When connection is made between chamber 1 and the passages 6 driving medium 75 will enter through 6 to expand in the section 7 only.

When the load decreases the entrance through 6 is first cut off so that driving medium only through passages 5 and at 10 80 enters. Upon further reduction of the load also the entrance through passages 5 will be cut off so that driving medium enters at the point 10 only.

85 At normal load and normal speed the position of the valve is as shown in Fig. 2. As the speed of the turbine decreases the governor weights 25 are drawn together by their springs. The bell crank levers are thus correspondingly moved so that the rod 24 and the link 23 will be moved upwardly, turning the lever 21 on the pivot 22 and moving the rod 20 downwards. The valve is thus turned in the direction of the arrow so that the openings 3 are allowed to pass driving medium to the passages 5. If more driving medium is required the movement will continue until the openings 4 will coincide with the passages 6.

At reduced load the operations take place in the reversed order.

The apertures 3, 4 of the regulating slide valve 2 are so arranged relatively to the passages 5, 6 that in the movement of the slide valve, from its normal position, in which the passages 5 and 6 are covered, in the direction of the arrow, Fig. 2 the passages 5 will first be uncovered and then the passages 6.

10 It is to be noted that more than two series of supply passages may be provided. Accordingly, the slide valve 2 must be formed with a corresponding number of sets of apertures.

15 I claim—

1. In an elastic fluid turbine the combination with a radial flow blade system, a stationary casing and a labyrinth packing between said blade system and said casing, of a single 20 fluid admission chamber located axially outside said packing, concentric series of fluid inlet passages leading from said chamber to intermediate stages of the blade system through said packing, an annular disk rotatably mounted in said chamber in engagement with said packing, said disk leaving an always 25 open connection at its inner circumference to the inlet point of the blade system, and concentric series of apertures formed in the disk to cooperate with said passages to control the successive admission of additional steam directly to said intermediate stages of the 30 blade system.

2. In an elastic fluid turbine the combination with a radial flow blade system, a stationary casing and a labyrinth packing between said blade system and said casing, of a single annular fluid admission chamber 35 located axially outside said packing, concentric series of fluid inlet passages leading from said chamber to intermediate stages of the blade system through said packing, an annular disk rotatably mounted in said chamber in engagement with said packing, said disk leaving an always open connection at its inner 40 circumference to the inlet point of the blade system, concentric series of apertures formed in the disk to cooperate with said passages, a governor, and connections between said 45 governor and said annular disk to rotate the latter in order thereby to control the successive admission of additional steam directly 50 to said intermediate stages of the blade system.

55 In testimony whereof I have signed my name.

OSCAR ANTON WIBERG.
